UNITED STATES PATENT OFFICE.

EDWARD E. FOSTER, OF BEVERLY, MASSACHUSETTS, ASSIGNOR TO C. C. BLAKE, INCORPORATED, OF BOSTON, MASSACHUSETTS, A CORPORATION OF NEW YORK.

LAST-MAKING MACHINE.

1,269,273.

Specification of Letters Patent. Patented June 11, 1918.

Application filed November 4, 1915. Serial No. 59,645.

To all whom it may concern:

Be it known that I, EDWARD E. FOSTER, a citizen of the United States, residing at Beverly, in the county of Essex and State 5 of Massachusetts, have invented a new and useful Improvement in Last-Making Machines, of which the following is a specification.

The present invention relates to wood cutting machines and more particularly to a machine for use in the manufacture of lasts.

The last used in the manufacture of Blake welt shoes is provided with a bottom which is separated from the upper-shaping surface of the last by a vertical shoulder.

The object of the present invention is to produce a machine for shouldering a last for use in the manufacture of Blake welt shoes.

To the accomplishment of this object, and such others as may hereinafter appear, the features of the invention relate to certain devices, combinations and arrangements of parts, hereinafter described, and then set forth broadly and in detail in the appended claims.

The various features of the present invention will be best understood from an inspection of the accompanying drawings illustrating the best form of the invention at present known to the inventor, in which,

Figure 1 is an elevation, partly in section, of the last making machine;

Fig. 2 is a detail in plan of the devices for supporting, guiding and feeding the leader;

Fig. 3 is a detail in plan of the mechanism beneath the platen;

Fig. 4 is a detail in sectional elevation looking toward the right, Fig. 2;

Fig. 5 is a diagrammatic plan illustrating the relation between the edge of the last bottom and the guiding flange on the leader;

Fig. 6 is a side elevation of the last;

Fig. 7 is a detail showing the cam surface on the leader at the toe thereof;

Fig. 8 is a sectional detail of the leader at the side thereof;

Fig. 9 is a diagrammatic plan showing the relation of the last and cutter during the bottom-forming operation;

Fig. 10 is a diagrammatic side elevation;

Fig. 11 is a sectional elevation of the finished last; and

Fig. 12 is a detail in elevation of the rotary cutter and its presser foot.

Referring now to Figs. 5 and 6 the last for use in the manufacture of Blake welt shoes is provided with an upper-shaping surface 1 and a bottom 2 which is separated from the surface 1 by a vertical shoulder 3. This construction raises the bottom of the last above the body portion thereof thus sharply defining the edge 4 of the last bottom. Described in general terms, the machine of the drawings is provided with a rotary cutter of less axial dimension than the last to form the shoulder 3 and the point of operation of this cutter is transferred along the last by automatic mechanism operating to move the support upon which the last is mounted over a horizontal table. During the transfer of the point of operation of the cutter along the last the relative position of the last and the cutter is corrected to maintain a uniform relationship between the last and the cutter notwithstanding the various slopes and lateral curves on the last bottom and thus locate the shoulder at the juncture between the bottom of the last and the upper-shaping surface thereof.

In the illustrated embodiment the last upon which the shoulder 3 is to be formed is jacked upon a work support 6 which is provided with runners 7 (Fig. 1) arranged to slide over a platen 8 secured to a bracket 9 mounted on a column 10. The work support 6 is secured to a leader 11 (Fig. 2) provided with a guiding flange 12 (Fig. 8) hereinafter referred to as "a contour of the last". As shown in Fig. 5 the projections of the edge of the finished bottom of the last at the sides thereof upon the plane of the leader coincide with the inside face of the guiding flange. At the toe the projections of the edge of the last bottom upon the plane of the leader fall within the guiding flange. This variation at the toe of the leader is for the accommodation of the toe-box which in a future shoe bottoming operation will be applied to the toe end of the insole which at that time will be flush with the toe end of the last bottom. When the

upper having the toe-box within it is lasted to the edge of the insole in accordance with the method of lasting practised in the Blake process the projections of the free edge of 5 the upper upon the plane of the leader will coincide with the inside face of the guiding flange throughout its length. Stated in another way, the projections upon the plane of the leader of the outside edge of the toe- 10 box secured in position on the toe of the insole positioned on the last will coincide with the guiding flange at the toe of the leader.

The leader is actuated to transfer the point of operation of the tool around the last 15 by a gear 13 (Figs. 1 and 2) which engages rack teeth 14 formed on the exterior face of the guiding flange 12. The gear 13 is secured to the upper end of a vertical shaft 15 (Fig. 1) which is driven from a horizontal shaft 20 16 through a worm 17 on the shaft 16 which meshes with a worm wheel 18 on the shaft 15. The shaft 16 loosely carries a pulley 19 which is driven from a motor 20, mounted on the base of the column 10, through a 25 belt 21. The pulley 19 is provided with a clutch member which is arranged to be engaged by a complementary clutch member 22 splined on the shaft 16. In order to shift the clutch member 22 on the shaft 16 and 30 thus clutch the pulley 19 to the shaft the clutch member 22 is provided with a peripheral groove 23 which is engaged by a pair of blocks 24 carried by the vertical arm of a bell crank lever 25 pivoted on the 35 column 10. The horizontal arm of the bell crank lever 25 is pivoted to the upper end of a rod 26 which is connected at its lower end to a treadle 27. With this construction pressure on the treadle slides the clutch 40 member 22 on the shaft 16 into engagement with the pulley 19 and thus clutches the shaft 16 to the source of power. The clutch member 22 is normally held away from the pulley 19 by a spring 28 one end of which 45 is operatively connected to the vertical arm of the bell crank lever 25 and the other end of which is connected to the column 10.

In order to swing the jack laterally as the point of operation of the tool is transferred 50 around the last to maintain the edge of the last in proximity to the tool in the line of feed the guiding flange 12 on the leader is engaged by a pin 29 (Fig. 2) arranged to engage inside the flange and by guide rolls 55 30 and 31 arranged to engage outside the flange. The guide pin 29 is formed upon the upper end of a vertical rod 32 (Fig. 1) which is loosely mounted in a bearing formed in the bracket 9. The rod 32 carries 60 a plane surfaced block 33 which is provided with a roll 34 (Fig. 4) embraced by a cam slot 35 formed in a vertical flange 36 of a horizontal slide 37 slidably mounted in the bracket 9. The slide 37 is connected to an 65 arm 38 projecting from a rock shaft 39

(Figs. 1 and 2) journaled in the column 10. A second arm 40 (Fig. 1) projecting from the rock shaft 39 is provided with a handle 41 by means of which the slide 37 may be actuated to cause the cam slot 35 70 to act upon the roll 34 and press the guide pin 29 below the guiding flange 12 and also below the surface of the platen 8. The guide pin 29 is eccentrically mounted on the rod 32 to permit it to traverse the short 75 curve at the toe of the leader. The guide pin is made semi-circular in the manner illustrated in Fig. 4 to avoid all danger of interference with the devices for securing the work support to the leader. 80

In order to hold the leader down upon the platen the exterior face of the flange at the upper end thereof is beveled as shown at 42 (Figs. 4 and 8). This beveled surface is engaged by the frusto-conical guide rolls 85 30 and 31. With this construction the guides 29, 30 and 31 have a three-point contact with the guiding flange and thus act to swing the work laterally during its feed. The axis about which the work swings 90 passes substantially through the point of operation of the tool. At least, the axis about which the leader swings passes through the point of operation of the tool during the traverse of the tool along the 95 sides of the last. In order to enable the rolls 30 and 31 to engage the flange at all times without binding as they traverse the reverse curves of the flange at the shank and around the toe the guide rolls 30 and 31 100 are journaled in a slide 43 (Fig. 4) mounted to slide in a guide-way 44 formed in the bracket 9. The rolls 30 and 31 are actuated in a direction to press them against the flange 12 by means of a spring 45 (Figs. 2 105 and 3). It has been proposed heretofore to connect the spring 45 directly to the slide 43. With this construction it was found that the pressure is decreased during the traverse of the rolls along a convex surface such as at the toe of the leader and that the pressure is increased during the traverse of the rolls along a concave surface such as at the shank of the leader. Owing to the great arc through which it is necessary 115 to swing the heavy leader and jack supported thereby during the traverse of the rolls around the toe it is found that with the construction referred to great pressure is brought to bear upon the rolls during their traverse of the toe. As the spring is pressing the rolls against the leader during their traverse of the toe with its minimum pressure there is a tendency for the leader to move away from one of the rolls and thus interrupt the desirable three-point contact of the guides with the flange. In order to maintain the three-point contact of the guides throughout their engagement with the flange the spring 45, instead of being 120 125 130

directly connected to the slide 43, is connected to the slide through a lever 46 (Figs. 2 and 3). This lever is arranged to vary its leverage inversely to variations in the tension on the spring. That is, the pressure on the rolls 30 and 31 is increased during their traverse of the toe of the leader and is decreased during their traverse along the shank of the leader. By increasing the pressure on the rolls during their traverse of the toe the leader is prevented from moving away from one of the rolls thus insuring the constant three-point contact of the guide rolls with the guiding flange. As the leverage of the swinging work is neutralized during the traverse of the rolls along the shank of the leader the pressure on the rolls may be safely decreased during their traverse of the shank in order to reduce their friction to a minimum. The lever 46 is pivoted at one end to the bracket 9. At its other end the lever is pivoted to a block 47 (Figs. 2 and 3) which loosely receives a rod 48 pivoted to an extension of the bracket. The spring 45 is coiled around the rod 48 and is interposed between the block 47 and a shoulder 49 on the rod. The lever 46 is pivoted intermediate its end by a short link 50 to the slide 43.

From an inspection of Figs. 3 and 4 it will be readily seen that the link 50 is connected to a rigid arm, that is, an arm not compressible longitudinally, of a toggle the other arm of which is yielding. With this construction the pressure of the rolls on the leader is at its minimum when the toggle approaches its made position and is at its maximum when the toggle approaches its broken position. As the slide is positioned farther to the right during the traverse of the rolls around the toe of the leader than during the traverse of the rolls along the shank of the leader it will be obvious that with the improved construction referred to the pressure of the rolls is increased during their traverse of the toe of the leader and is decreased during their traverse along the shank of the leader. The improved construction consequently insures the engagement of the three guides 29, 30 and 31 with the guiding flange at all times during their traverse thereof. While the rigid arm of the toggle as shown in the illustrated embodiment of the invention is a lever of the second order it will be readily understood by those skilled in the art that levers of other orders may comprise the rigid arm of the toggle.

To withdraw the guide rolls 30 and 31 from the guiding flange 12 at the same time that the guiding pin 29 is withdrawn therefrom the slide 37 is provided with a cam slot 51 (Figs. 2 and 3) which embraces a roll 52 carried by the slide 43. With this construction a downward movement of the

handle 41 simultaneously depresses the guide pin 29 and withdraws the guide rolls 30 and 31 from the flange 12. It will be noticed from an inspection of Figs. 3 and 4 that the cam slot 51 is wide enough to permit the roll 52 to move loosely therein when the guide rolls 30 and 31 yield to the curves of the leader. In order to hold the slide 36 in a normal operative position with the handle 41 elevated the arm 38 is pivoted to a rod 53 (Fig. 4) which passes loosely through a lug 54 on the column 10. Interposed between the lug 54 and a shoulder 55 on the rod is a spring 56 which is coiled around the rod. The movement of the slide 37 is limited in both directions by a pair of pins 57 and 58 (Fig. 3) arranged to alternately engage the opposite sides of the bracket 9.

The tool for forming the shoulder 3 consists of a rotary cutter 59 (Figs. 1 and 12) of less axial diameter than the last, that is, the vertical height of the cutter is less than the vertical height of the last. The cutter comprises a conical cutting face 60 which forms the shoulder 3 and a concaved cutting face 61 which shapes the upper-shaping surface of the last adjacent the base of the shoulder 3. The cutter is mounted in operative position relative to the last so that an element of the conical face 60, hereinafter called the cutting element, is in a vertical plane intersecting the axis about which the last support is swung to maintain the curved edge on the last bottom in the line of feed. The two faces 60 and 61 are joined by a circular edge 62. The circular edge 62 rotates in an inclined plane so that the projections thereof on vertical and horizontal planes generate ovals having their major axes horizontal. The dotted line representations of the cutter in Figs. 9 and 10 illustrate the shape of the circular edge 62 when generated upon horizontal and vertical planes respectively. The size and inclination of the circular edge 62 determine the size and position of a rotary cutter which will cut into the wood of the last to the same depth and at the same angle notwithstanding the various longitudinal and lateral curves on the last bottom. To this end the largest curve which would engage the last on a rise or drop without penetration below the line of the contemplated cut was first determined. Then the largest curve was determined which would fit into the reverse curves along the edge of the last bottom without extension within the edge of the last bottom. These two curves were found to be elliptical in form and after forming the ellipses in vertical and horizontal planes, respectively, a circle was determined which, when located in an incline plane, would project the ellipses in the horizontal and vertical planes referred to. The determination of this circle fixed the size and location

of the cutter. With this construction and arrangement the uniform engagement of the cutter with the horizontal and lateral curves of the work is insured. That is, notwithstanding the various slopes and reverse curves on the last the cutter 59 will engage all points around the last in the same manner.

The cutter 59 is secured at the end of an inclined shaft 63 (Fig. 1) which is journaled in a cutter head 64 formed on a counterbalance slide 65. The slide 65 is mounted to slide vertically in ways formed on a second slide 66 mounted to slide horizontally 15 in ways formed on the column 10. The shaft 63 is rotated by a belt 67 which passes over a pulley 68 on the shaft 63, an idler pulley 69 on the cutter head, and a pulley 70 on a shaft 71 which is driven by a motor 72 on the cutter head 63.

During the transfer of the point of operation of the cutter 59 around the last the cutter head 64 rises and falls in accordance with the various slopes on the last bottom.

To this end the head 64 carries a frustoconical roll 73 which is arranged with its broader base directed toward the cutter 59 and is mounted to travel over an end surface of the last within the line of cut. The roll 73 is journaled in an arm 74 which is pivoted at 75 on the cutter head 64. In order to permit the continued rotation of the cutter 59 and at the same time prevent its operation on the last the arm 74 may be turned about the pivot 75 to bring the roll 73 beneath the cutter or between the cutter and the last. To this end the cutter head 64 carries a horizontal shaft 76 (Fig. 1) provided with an eccentric 77 which works 30 in an elongated opening 78 formed in the arm 74. The shaft 76, outside the arm 74, is also provided with a double-face collar or disk 79 (Fig. 12) which carries a rod 80 by means of which the operative may 35 rotate the eccentric 77 and thus raise and lower the presser foot 73 about its pivot 75. In order to lock the presser foot 73 in its elevated and depressed positions the arm 74 carries a spring-pressed pin (not 40 shown) which snaps into holes 81 and 82 at the extreme positions of the presser foot in both directions. This locking device holds the parts locked under pressure on the presser foot in the direction of the arrows (Fig. 12). The parts of the locking device readily separate, however, when the handle 80 is operated to rotate the eccentric 77.

During its operation upon the sides of the last the cutter forms a shoulder the projections of which upon the plane of the leader coincide with the guiding face 12. In order to accommodate for the toe-box variation hereinbefore referred to the slide 66 is provided with a feeler or cam follower

83 (Figs. 1 and 2) interposed between the rolls 30 and 31, which engages the bevel 42 on the outside face of the guiding flange. The feeler is pressed against the bevel 42 by a coiled spring 84 one end of which is connected to a bracket 85 depending from the slide 66 and the other end of which is connected to the bracket 9. The bevel 42 is formed at the sides of the leader to maintain the cutter in such position that the 75 projections of the edge of the last bottom formed thereby will coincide with the inside face of the guiding flange 12. At a point corresponding to the position of the end of the toe-box in a lasted shoe the bevel 80 42 commences to change to a cam face 86 (Fig. 7) having more taper. With this construction the cutter 59 is shifted transversely of the feed during its traverse of the toe of the last to form an edge the projections of which upon the plane of the leader fall within the guiding flange.

It will be clear to those skilled in this class of machines and with the general objects of the present invention in view that changes may be made in the details of structure, the described and illustrated embodiment thereof being intended as an exploitation of its underlying essentials the features whereof are definitely stated in their true scope in the claims hereto appended.

What is claimed as new, is:—

1. A last making machine, having, in combination, a support for a last in process, a rotary cutter of less axial dimension than the last to form a shoulder thereon, means for relatively moving the support and the cutter to transfer the point of operation of the cutter along the last, and means engaging an end surface of the last and controlling the relative vertical position of the cutter and the last by variations of said end surface from a plane to maintain a uniform relation between the cutter and the bottom of the last and thus locate the shoulder at the juncture of the bottom of the last with the upper-shaping surface thereof.

2. A last making machine, having, in combination, a support for a last in process, a rotary cutter of less axial dimension than the last to form a shoulder thereon, means for relatively moving the support and the cutter to transfer the point of operation of the cutter along the last, and means engaging a contour of the last and controlling the relative horizontal position of the cutter and the last by variations of said contour from the point of operation of the cutter to maintain a uniform relation between the cutter and the bottom of the last and thus locate the shoulder at the edge of the bottom.

3. A last making machine, having, in combination, a support for a last in process, a rotary cutter of less axial dimension than the

last to form a shoulder thereon, means for relatively moving the support and the cutter to transfer the point of operation of the cutter along the last, and mechanism to 5 maintain a uniform relation between the cutter and the bottom of the last and thus locate the shoulder at the juncture of the bottom of the last with the upper-shaping surface thereof, comprising means engaging an end surface 10 of the last controlling the relative vertical position of the cutter and the last by variations of said end surface from a plane, and means engaging a contour of the last controlling the relative horizontal position of the 15 cutter and the last by variations of said contour from the point of operation of the cutter.

4. A last making machine, having, in combination, a support for a last in process, a 20 rotary cutter having a conical cutting face, means for feeding the support longitudinally past the cutter, and means for swinging the support laterally during its feed longitudinally to maintain the reverse curves on the 25 bottom of the last in the line of feed, said swinging movement taking place about an axis coinciding with the cutting element of the cutter.

5. A last making machine, having, in combination, a support for supporting a last, and a conical cutter of less axial dimension than the last and arranged with its cutting element in a vertical plane, to form a vertical shoulder at the juncture of the bottom of 35 the last with the upper-shaping surface thereof.

6. A last making machine, having, in combination, a support for supporting a last, and a conical cutter, of less axial dimension 40 than the last and arranged with its cutting element in a vertical plane, to form a vertical shoulder at the juncture of the bottom of the last with the upper-shaping surface thereof, said cutter having a concaved cutting face to 45 shape the upper-shaping surface of the last adjacent the base of the shoulder.

7. A last making machine, having, in combination, a support for a last in process, a conical cutter of less axial dimension than 50 the last and arranged with its cutting element in a vertical plane, to form a vertical shoulder at the juncture of the bottom of the last with the upper-shaping surface thereof, said cutter having a concaved cutting face to shape the upper-shaping surface 55 of the last adjacent the base of the shoulder, means for moving the support to transfer the point of operation of the cutter along the last, and means for correcting the relative position of the support and cutter during 60 the transfer of the point of operation of the cutter along the last to maintain a uniform relationship between the cutter and the last notwithstanding variations in the 65 slope and edge curvature on the last bottom

and thus locate the shoulder at the juncture of the bottom of the last with the upper-shaping surface thereof.

8. A last making machine, having, in combination, a support for a last in process, a 70 cutter to form a shoulder on the last, means for feeding the support longitudinally and swinging it laterally to transfer the point of operation of the cutter along the last, and means for correcting the relative position of 75 the support and cutter during its transfer along the last to maintain a uniform relationship between the support and cutter notwithstanding variations in the slope and edge curvature of the last bottom and thus 80 locate the shoulder at the juncture of the bottom of the last with the upper-shaping surface thereof.

9. A last making machine, having, in combination, a support for a last in process, a 85 plural cutting means to form a vertical cut in the last bottom and a second lateral cut in the upper-shaping surface of the last joining the vertical cut at the base thereof, means for relatively moving said means and 90 the support to transfer the point of operation of said means along the last, and means engaging an end surface of the last and a contour of the last, respectively, for correcting the relative position of the cutting 95 means and the support notwithstanding variations in the slope and edge curvature of the last bottom.

10. A last machine, having, in combination, a support for a last in process; a leader 100 carried by the support and having a guiding flange; a rotary cutter operating to form a shoulder at the sides of the last bottom, the projections of which upon the plane of the leader coincide with the guiding flange; 105 means for relatively actuating the support and cutter to transfer the point of operation of the cutter around the last; and means for relatively shifting the support and cutter during the transfer of the point of operation of the cutter around the toe of the last to form a shoulder the projections of which upon the plane of the leader fall within the guiding flange, substantially as described. 110

11. A last machine, having, in combination, a support for a last in process; a leader carried by the support and having a guiding flange; a rotary cutter operating to form a shoulder at the sides of the last bottom, the projections of which upon the plane of the 115 leader coincide with the guiding flange; means for actuating the leader to transfer the point of operation of the cutter around the last; and means for relatively shifting the support and cutter during the transfer 120 of the point of operation of the cutter around the toe of the last to form a shoulder the projections of which upon the plane of the leader fall within the guiding flange, substantially as described. 125

12. A last machine, having, in combination, a support for a last in process; a leader carried by the support and having a guiding flange; a rotary cutter operating to form a shoulder at the sides of the last bottom, the projections of which upon the plane of the leader coincide with the guiding flange; means for actuating the leader to transfer

the point of operation of the cutter around the last; and means for shifting the cutter 10 during the transfer of the point of operation of the cutter around the toe of the last to form a shoulder, the projections of which upon the plane of the leader fall within the guiding flange, substantially as described. 15
